UNITED STATES PATENT OFFICE.

FRANK S. LANG, OF SEATTLE, WASHINGTON.

STOVE.

990,884.

Specification of Letters Patent. Patented May 2, 1911.

Application filed March 20, 1909. Serial No. 484,680.

To all whom it may concern:

Be it known that I, FRANK S. LANG, a citizen of the United States, residing at Seattle, in the county of King and State of Washington, have invented certain new and useful Improvements in Stoves, of which the following is a specification.

This invention relates to cooking stoves. Its object is to furnish improved means whereby the heat products derived from the fire are utilized to a maximum extent for cooking purposes and to promote the combustion of the fuel so that an extremely effective and economical fire may be maintained.

The invention consists in the novel construction and combination of the parts thereof in a stove as will appear in the following description taken with reference to the accompanying drawings, wherein—

Figure 1 is a longitudinal vertical section of a stove constructed in accordance with my invention. Fig. 2 is a cross sectional view taken through 2—2 of Fig. 1. Fig. 3 is an end elevation shown partly broken away. Fig. 4 is a fragmentary perspective view of the grade frame shown detached and drawn to an enlarged scale.

The reference numeral 5 designates the back end of the stove casing; 6 the front end thereof; and 7 and 8, respectively, the bottom and top walls of the same. 9 represents an oven which is inclosed by a top wall 10, a back wall 11, a bottom wall 12 and a front wall 13. The latter is spaced from the front casing wall to provide a furnace comprised of an ash-pit 14 and a fire-pot 16 thereabove; while the other of said oven walls are spaced from the respective walls of the casing to afford communicating flues 15, 15' and 15''. The wall 12 is continued, as at 12', to the casing front, as shown in Fig. 1 to have the flue 15'' extend to the casing wall 6, which is provided with an opening 17 making communication with an uptake flue 18 positioned in front of the casing wall 6 and having an opening 19 at the top for a chimney connection. By having the terminal flue 15'' pass beneath the ash-pit much of the heat from the exhaust gases are transmitted through the partition 12' into the ash-pit.

Above the ash-pit 14 is a horizontally arranged frame comprised of end members 20 and side members 21. The end members are

each provided along its inner edge with an upturned flange 20' and in the web portions 20'' are pluralities of openings 22 making communication with the space below with that above. Said side members are provided with series of spaced notches 21' to receive lugs 23 projecting from the opposite ends of the grate-bars 23' and serving as pivotal supports whereupon the grate-bars may be oscillated. Upon one end of each of the grate-bars is provided an additional lug 23'' severally socketed in spaced holes in a shaking-bar 24 which extends through an aperture 25 in the front wall 6 of the stove, as shown in Fig. 3. This aperture is formed to one side with a step 25' for the purpose of accommodating the shaker-bar when the latter is elevated in causing the grate-bars to be brought into close relation with each other, as represented in Fig. 1, and by such step the shaker-bar is reliably held to retain the bars in such positions.

The liners are formed to have along their top edges laterally extending flanges 27 which project beyond the plane of the respective outer faces 26' of the liners, and at the juncture of the flanges with the liner bodies are nosings 28 which protrude beyond the opposite faces. Subjacent to said nosings are holes 29 extending through the respective liners. Extending from the liner faces 26' are studs 30 serving to maintain the liners at their bottoms in contact with the flanges 20' of the respective members and clear of the openings 22 in such members. The flange of the liner which is next to the casing front 6 serves to support the top end of the liner in spaced relation with respect to the front, while a like office is rendered as to the other liner with respect to the oven-wall 13 by studs, such as 31.

By the aforescribed devices wing compartments 32 are provided which are in communication with the fire-box through the holes 29 and with the ash-pit by the openings 22. Extending through the uptake flue 18 and making communication between the compartment 14 and the atmosphere exteriorly of the stove is an air-conduit 33 and for which is provided a damper-plate 34.

In operation, the fire is built in the usual manner over the grate-bars 23' and when it is properly burning the bars are manipulated through the medium of the shaker-bar 24 to effect the inclination of the grate-

bars into the positions in which they are illustrated in Fig. 1 and thus closing the interstices between the grate-bars to prevent a direct flow of air into the fire-box 5 from the ash-pit. The air for combustion purposes, as indicated by the darts in Fig. 1, first enters the ash-pit 14, whence it passes through holes 22 into the wing compartments 32 and from the latter, by way of the 10 holes 29, into the fire-box and above the bed of fuel to contribute to the burning of the consumable gases which are liberated therefrom.

The unconsumable gases flow, as indicated 15 by the feathered arrows in Fig. 1, at a high temperature from the fire-box by the flues 15, 15' and 15'' and through the opening 17 into the smoke-uptake 18, whence they escape through the chimney connections. In 20 taking the above described course the hot gases act against the stove top, or cover, 8 and also upon the three walls 10, 11 and 12 to afford heat to the oven, and therebeyond contacting with the walls 12' and 6 and also 25 impinging against the walls of the conduit 33. The heating of the walls of the ash-pit 14 and of the said conduit effect the heating of the air which flows through the latter into and through this compartment which 30 together with the heat absorbed from the liners 26, will effect the raising of the temperature of the air as supplied to the firebox to readily combine with the combustible products of the fuel and maintain a fire of 35 relatively high efficiency. By heating the air prior to mingling with the volatile fuel-gases, such gases are not chilled to any appreciable extent and consequently the combustion is unimpaired.

40 The advantages of the invention reside principally in the coöperation with a grate which is adapted to be closed against the passage of air therethrough to cause the air for combustive purposes to pass into the fire above the fuel, of the means for heating such air through subjecting the same to the residual heat from the fire and subse-

quent to the utilization of such heat as is employed in cooking operations.

Having described my invention, what I 50 claim, is—

1. In a stove, an oven, a fire box arranged at the front end of said oven and having openings near the upper ends of the walls thereof, the walls of said box so disposed as 55 to provide winged compartments an ash pit arranged below the fire box and at the front end of said oven, a frame at the lower end of the fire box and provided with openings and notches, a normally open grate mounted 60 in the notches of said frame, means for closing the grate to prevent passage of air therethrough, the openings of said frame and fire box establishing communication between the ash pit and the upper part of the firebox by 65 way of said winged compartments, a flue communicating with the atmosphere for conveying air to said ash pit, and means in connection with the walls of said oven to provide flues for conducting the products 70 of combustion against the outside of the first-mentioned flue for heating it.

2. In a stove, the combination with an 75 oven, a firebox and an ash-pit arranged at one end of said oven, and means in connection with the walls of the oven to provide flues for conducting the products of combustion from the fire box of a grate adapted to be adjusted to prevent the passage of air therethrough, liners within said firebox and 80 arranged to afford compartments upon opposite sides of the firebox which respectively communicate with both the ash-pit and the firebox, an uptake connection communicating with the flues, and an air conduit extending through said uptake connection and 85 arranged to be exteriorly engaged by the gases escaping through said uptake connection and leading to the ash pit.

FRANK S. LANG.
